MACHINE FOR WRAPPING RYE BREAD

Frank Reinhold Schmitt, Queens Village, N. Y.,
assignor to American Machine & Foundry Com-
pany, a corporation of New Jersey

Application July 2, 1930, Serial No. 465,427

17 Claims. (Cl. 93—2)

This invention relates to an improvement in wrapping machines and methods, and particularly to a rye bread folding attachment for such machines.

5 The main object of this invention is to adapt wrapping machines of the type shown in my co-pending application Serial No. 334,479, filed January 23, 1929, to wrap rye bread or similar shaped articles which cannot be wrapped on machines of that type. A further object is the production of a novel method of wrapping rye bread or similar shaped articles. With these and other objects not specifically mentioned in view, the invention consists in certain constructions and combinations hereinafter fully described and then specifically set forth in the claims hereunto appended.

In wrapping rye bread, because of its pointed ends, it is desirable to fold the ends of the wrapper downward and have the flap at the bottom of the loaf. To allow for this, the folding table of the wrapping machine is cut away at the sides and a portion of the folding mechanism is placed over the openings so formed as hereinafter fully described.

The novel rye bread end-folding mechanism comprises a pair of pivotally mounted side tuckers which tuck the rear side of the overhanging ends of the wrapper inwardly against the loaf; a pair of vertically inclined stationary folders which gradually press down the top end-flaps of the wrapper as the loaf is carried forward in the machine; and a pair of horizontally inclined stationary folders which push the then overhanging end-flaps back under the loaf as it passes over the cut away portions of the bottom folder plate, thereby making the bottom folds at the ends of the loaf.

In carrying the invention into effect, there is provided a process of, and apparatus for, wrapping an article partially encircled by a wrapper. In the best practice of the invention, the process is carried out by tucking the rear side only of the wrapper which partially encircles the article, then completely encircling the article in the wrapper, folding the end-flaps of the wrapper over on the bottom of the article, and sealing the ends of the wrapper. All the apparatus that is essential to the practice of the invention in its simplest form is means for tucking the rear side only of the wrapper, means for folding the end-flaps of the wrapper over on the bottom of the article, means for sealing the ends of the wrapper, and means for moving the article from the tucking means through the folding means to the sealing

means. The tucking means, in the best practice of the invention, includes a pair of tuckers fixed to a transfer member which is movable from an inclined position, at which it receives and tucks the rear side only of a wrapper partially encircling the article, to a horizontal position, at which the article is moved to the folding means and has the wrapper drawn about it to completely encircle it. In the best practice of the invention, also, the folding means includes a folding table, the forward edge of which draws the wrapper about the article, as hereinbefore described, and stationary folding plates and folders cooperating to fold the ends of the wrapper on the bottom of the article, and the sealing means includes a 15 heated table. The novel package resulting from the practice of the method and apparatus comprises an article encircled by a wrapper, the ends of which have been closed in the manner outlined in the steps of the process described above.

In the accompanying drawings, which form a part of this specification and in which like characters of reference indicate the same or like parts:

Fig. 1 is a plan view of the improved rye bread 25 folding device, the side frames and loaf forwarding means being omitted;

Fig. 2 is a side elevation of the mechanism shown in Fig. 1;

Fig. 3 is a sectional view taken on the line 30 3—3 of Fig. 1 showing the relation of the package and the folder plates;

Figs. 4 to 10A show the different folding stages of the package as it travels through the machine; and

Fig. 11 is a perspective view of the finished package.

Referring to Figs. 1, 2 and 3 of the drawings, the stationary side frames 20 of the wrapping machine described in the above mentioned application have slidably mounted therein the slide bars 21 on which are fixed longitudinally extending frame members 22 carrying the studs 23 to which the stationary vertical folding walls 24, 25 and 26 are attached, this construction also including 40 springs mounted on the studs to permit yielding movement of the folding walls in accordance with variations in the length of the loaves and constituting a part of the standard equipment of ordinary bread wrapping machines. Heating 50 units, not shown, carried by the folding walls 25 and 26 radiate heat to the novel rye bread folding device which is attached to the folding walls 25 and 26 and will now be described.

The support plates 27 of the folding device 55

carry a number of studs which fit into corresponding holes in the folding walls 25 and 26 and are rigidly held in place thereon by the nuts 28. The longitudinal vertically inclined folders 29, which have their further or rear ends horizontally disposed, carry the angles 30 which are attached to the support plates 27 by the studs 31 having the nuts 32 threaded thereon. The short horizontal folders 33 are fastened at their front ends to the support plates 27 by the screws 34 and have their other ends offset horizontally and downwardly. The front ends of the folders 33 rest on the folding table 35 having the slots 36 receiving the front edges of the folders 33 which are bent downwardly therein. At the extreme end of the support plate 27 are attached the spring plates 37 pressing against the deflector plates 38 carrying the flappers 39, the deflector plates 38 being angle-shaped and having the slots 40 in their base into which are inserted the guide screws 41 threaded into the inclined folders 29. The folding table 35 and sealing table 42, over which the package passes while being folded, and sealed, are supported by parts of the frame of the machine, not shown. The transfer member 43 which is actuated by a cam, not shown, is pivotally supported by the side frames 20 and carries the side tuckers 44 attached to the arms 45, which are rigidly attached to the transfer member.

30 The operation of the rye bread folding device in carrying out the improved method to form the novel package is as follows:

The loaf, or other article, P, as in the ordinary wrapping machine is delivered by any suitable means, not shown, to an inclined plate 46 disposed below the table 35 and then moved in the direction of the arrow, as shown in Figs. 4 and 4A, by the pusher 47, engaging and taking along with it the end of the continuous web W of waxed paper, tin-foil or other suitable material, which is unwound from a reel, not shown, and hangs downwardly in a position in front of the plate 46 after the wrapper for the preceding loaf has been cut. Upon engaging the edge of the transfer member 43, which is then in its lowermost position 43', the wrapper end is folded under the loaf P and the overhanging ends of the wrapper are tucked inwardly at the rear side of the loaf by the side tuckers 44, as shown in Fig. 5. The transfer member then ascends into position 43, carrying the wrapper web with it, thereby drawing the wrapper over the top and forward side of the loaf, with the web W hanging between the adjacent edges of the transfer 43 and folding table 35, as seen in Fig. 6. While in this position, the web is clamped and cut by suitable means, not shown. The side tuckers 44 are formed with broad block shaped ends 48, thereby preventing the loose end-flaps from catching in the ends of the tuckers.

60 The loaf is now moved from the transfer member 43 onto folding table 35 in the direction of the arrow shown in Fig. 6, by pusher members 52 supported by the moving chains 51, thereby carrying the hanging wrapper end with it and folding it under the loaf as it engages the edge of the folding table 35. While the loaf thus moves forward, the overhanging end-flaps of the wrapper W adjacent the top and forward side of the loaf are pressed downward by the inclined folding plates 29, as seen in Fig. 7. In proceeding forwardly, the loaf P is engaged by the horizontal folders 33 which are so disposed as to provide, between plates 29 and folders 33, slots 49 (Fig. 3) 75 into which enter the downwardly hanging end-

flaps of the wrapper W, as seen in Figs. 8 and 9. Since both sides of the folding table 35 are cut away, they permit the downwardly hanging flaps of the wrapper to be folded upwardly by the tapered portions 50 of the folding plates 29 which progressively fold the flaps inward under the tapered ends of folders 33. When the package reaches the horizontal tapered part of the folding plates 29, the bottom fold is gradually formed as the loaf travels along plate 29, as seen in Figs. 10 and 10A. When the package approaches the ends of the folders 33, it enters between the resilient strips 38 which hold the ends of the wrapper in place until they reach the heated sealing table 42, having a heating unit 53, the flappers 39 then holding the end-flaps of the package while the bottom-flap is being sealed. The package after sealing is carried onto a conveyor and is delivered from the machine as a finished package shown in Fig. 11.

20 What is claimed is:

1. The combination with means for tucking the rear side only of a wrapper encircling an article, of mechanism for simultaneously folding the overhanging end-flaps of the wrapper adjacent the top and forward sides of the article downwardly over the ends thereof and then folding the downwardly hanging flaps thus formed over on the bottom of the article, a device for sealing the ends of the wrapper, and means for moving the article from the tucking means through the folding means to the sealing device.

25 2. The combination with means for tucking the rear side only of a wrapper encircling an article, of mechanism for folding the end-flaps 35 of the wrapper over on the bottom of the article, a device for sealing the ends of the wrapper, and means for moving the article from the tucking means through the folding means to the sealing device, said tucking means including a 30 pair of stationary tuckers.

3. The combination with means for tucking the rear side only of a wrapper encircling an article, of mechanism for folding the end-flaps of the wrapper over on the bottom of the article, 45 a device for sealing the ends of the wrapper, and means for moving the article from the tucking means through the folding means to the sealing device, said tucking means including a transfer member movable from an inclined position at 50 which it receives the article partially encircled by its wrapper to a horizontal position at which the article is moved to said folding mechanism to completely encircle the article in its wrapper, and stationary tuckers supported by said transfer member adapted to tuck the wrapper when said transfer member is in its inclined position.

4. The combination with means for tucking the rear side only of a wrapper encircling an article, of mechanism for folding the end-flaps of the wrapper over on the bottom of the article, a device for sealing the ends of the wrapper, and means for moving the article from the tucking means through the folding means to the sealing device, said mechanism including folding plates having a vertically inclined portion adapted to turn the end-flaps of the wrapper downwardly and a horizontal portion adapted to fold the downwardly turned end-flaps on the bottom of the article.

5. The combination with means for tucking the rear side only of a wrapper encircling an article, of mechanism for folding the end-flaps of the wrapper over on the bottom of the article, a device for sealing the ends of the wrapper, 75

and means for moving the article from the tucking means through the folding means to the sealing device, said mechanism including folding plates having a vertically inclined portion 5 adapted to turn the end-flaps of the wrapper downwardly and a horizontal portion adapted to fold the downwardly turned end-flaps on the bottom of the article, and horizontally disposed folders having a portion spaced from said folding plates to provide a slot for guiding said end-flaps.

6. The combination with means for tucking the rear side only of a wrapper encircling an article, of mechanism for folding the end-flaps 15 of the wrapper over on the bottom of the article, a device for sealing the ends of the wrapper, and means for moving the article from the tucking means through the folding means to the sealing device, said mechanism including a folding table having cut away portions and folding plates arranged to fold the end-flaps of the wrapper on the bottom of the article above said cut away portions.

7. The combination with means for tucking 25 the rear side only of a wrapper encircling an article, of mechanism for folding the end-flaps of the wrapper over on the bottom of the article, a device for sealing the ends of the wrapper, and means for moving the article from the tucking 30 means through the folding means to the sealing device, said mechanism including resilient strips for holding the folded ends of the wrapper in place until they reach said sealing device, and flappers for holding the end-flaps of the wrapper in place on said sealing device.

8. The combination with means for tucking the rear side only of a wrapper encircling an article, of mechanism for simultaneously folding the overhanging end-flaps of the wrapper adjacent 40 the top and forward sides of the article downwardly over the ends thereof and then folding the downwardly hanging flaps thus formed over on the bottom of the article, a device for sealing the ends of the wrapper, and means for moving the 45 article from the tucking means through the folding means to the sealing device, said device including a heated table.

9. The combination with means for tucking the rear side only of a wrapper encircling an article, of mechanism for simultaneously folding the overhanging end-flaps of the wrapper adjacent the top and forward sides of the article downwardly over the ends thereof and then folding the downwardly hanging flaps thus formed 55 over on the bottom of the article.

10. The combination with means for tucking the rear side only of a wrapper encircling an article, of mechanism for folding the end-flaps of the wrapper over on the bottom of the article, 60 said means including stationary block shaped tuckers, said mechanism including stationary folding plates and stationary folders cooperating to fold the end-flaps of the wrapper on the bottom of the article at both ends of the latter.

11. The combination with means for tucking the rear side only of a wrapper encircling an article, of mechanism for folding the end-flaps 65 of the wrapper over on the bottom of the article, said mechanism including stationary folding plates and stationary folders cooperating to fold the end-flaps of the wrapper on the bottom of the article at both ends of the latter.

12. Mechanism for folding the end-flaps of a wrapper over on the bottom of the article which it encloses, comprising a folding table having cut away portions, folding walls which are mounted for yielding movement to accommodate variations in the lengths of the articles, folding plates and folders attached to said walls and cooperating to fold the end-flaps of the wrapper over on the bottom of the article above said cut away portions of said table, flappers arranged to engage 10 the folded ends of the wrapper to hold the folded flaps in position on the bottom of the article, and spring plates yieldingly supporting said flappers.

13. The combination with means for tucking in the rear side only of a wrapper encircling an article, of devices for forwarding the article, and mechanism for folding the end flaps of said wrapper under the article, including a stationary folder having a continuous folding surface extending downwardly alongside of the path of the article 20 from a position above the end flaps of the wrapper to the bottom of the article and thence diagonally under the article toward the center thereof to fold said end flaps under the article.

14. Means for folding the end flaps of a wrapper encircling an article comprising in combination means for forwarding the encircled article and a stationary folder having a continuous folding surface extending downwardly along the path of the article from a position above the end flaps 30 of the wrapper to the bottom of the article and thence diagonally under the path of the article and toward the center thereof to fold said end flaps under the article.

15. Means for folding the end flaps of a wrapper encircling an article comprising in combination means for forwarding the encircled article and a stationary folder having a continuous folding surface extending downwardly along the path of the article from a position above the end flaps 40 of the wrapper to the bottom of the article and thence diagonally under the path of the article and toward the center thereof to fold said end flaps under the article, and mechanism having an auxiliary folding surface spaced from and paralleling the portion of the stationary folder extending under the article.

16. The process of wrapping a loaf of rye bread, which comprises partially encircling the loaf in a wrapper having end flaps overhanging the ends 50 of the loaf, then tucking in the end flaps of said wrapper adjacent one side of said loaf, then completely encircling the loaf in said wrapper so that the longitudinal edges of the wrapper are in overlapping relation on the bottom of the loaf, and then simultaneously folding the end flaps of said wrapper adjacent the top, the other side and bottom 55 of the loaf over onto the bottom thereof.

17. The process of wrapping a loaf of rye bread, which comprises partially encircling the loaf in a wrapper having end flaps overhanging the ends of the loaf, then tucking in the end flaps of said wrapper adjacent one side of the loaf, then completely encircling the loaf in said wrapper so that the longitudinal edges of the wrapper are in overlapping relation on the bottom of the loaf, then simultaneously folding the end flaps of said wrapper adjacent the top, the other side and bottom 60 of the loaf over onto the bottom thereof, and heat sealing the flaps folded over the bottom of the loaf.
